UNITED STATES PATENT OFFICE.

LESLIE R. McDONALD, OF WESTMOUNT, ONTARIO, CANADA.

DISPLAY APPARATUS.

Application filed November 6, 1923. Serial No. 673,201.

My invention relates to that class of display apparatuses wherein a considerable number of flexible placards are wound around a rotatable holder and are allowed to successively unroll and drop into view position as the holder revolves, step by step; and my improvements are particularly directed to means for preventing derangement of the apparatus when subjected to jars and movements, such as arise, for instance, in railway cars, or similar vehicles, in which the display apparatus may be mounted, and to the details of construction which will be hereinafter pointed out.

In the drawings, Fig. 1 is a side elevation of mechanism embodying my improvements; Fig. 2 is a front elevation of the same taken on a reduced scale; Fig. 3 is a detail, taken on the line 3—3 of Fig. 2, looking to the right, a roll of placards being indicated around the carrier; and Fig. 4 is a side view of the release actuating pawl arm, the pinion rotated thereby being shown in section. Figs. 3 and 4 are on a reduced scale compared with Fig. 1.

Similar reference numerals designate similar parts in both figures.

The apparatus which is assembled in and carried by a frame 1, embraces a rotatable shaft 2, provided with means, such as disk heads 3, 3, to which a plurality of flexible placards 03 may be secured at one end in a suitable manner, as by attaching each placard 4 to a rod or bar 5, the ends of which are carried by the disks. As the means for attaching these placards to the rotatable shaft forms no part of my present invention, I have omitted, for clearness, all of the placards but one. For those skilled in the art will well understand how to mount a series of such placards in the carrier disks.

The shaft 2 rotates in suitable bearings in the frame 1, and is actuated, step by step, through a cam-actuated drag pawl arm 6, and detent arm 7, carried by a shaft 8, driven through a gear 9, meshing with a worm 10 on the shaft 11 of an electric motor 12, mounted in the frame 1.

The shaft 8 also carries a cam 13, around which a cam race 14 is formed by means of the guide 15 which is supported by suitable studs 16, 16 fastened to the gear wheel 9. And in the cam race travels the arm 17 of a crank arm 18, loosely journalled

on the shaft 2, so that as the cam 13 evolves the arm 18 will be rocked on the shaft 2, causing its attached arm 19 to reciprocate back and forth, carrying with it the rod 20, the opposite end of which is supported by a similar arm 21, also loosely journalled on the shaft 1, so that the pawls 22, 23, alternately engaging and pulling forward the free ends of the placards, to cause them to unroll freely, will be reciprocated at the proper times.

These pawls are alternately raised and lowered into engagement with the placard roll through the agency of arms 24, and 25 attached to the respective pawls, the free ends of the arms traveling over cams 26, 27 on a shaft 28 supported in brackets on the frame 1 and rotated step by step by a pawl arm 29 reciprocated by a cam 30 on the shaft 8, and engaging with a pinion 30 on shaft 28.

The ends of a flanged bar 34 are carried by slotted brackets on the frame 1, and may be adjusted therein radially of the placard carrier, and secured in position as by set screws 66. This flanged bar is preferably provided with extensions 65, 65, adapted to be near to the placard roll and to keep the placards in proper position. In Fig. 3 a socket is indicated by broken lines in the flanged bar 34 to give clearance for the ends of the arms 24 and 25. The mechanism for releasing the placards step by step is the subject of a separate application now pending in the Patent Office: Serial No. 625,928, filed March 17th, 1923, and I will not therefore describe it in greater detail; the purpose of the present description being to illustrate the specific form of cam race by which the arm 18 is oscillated, and wherein an open race which is guarded by a track on either side is employed, so that the action of the cam will at all times be positive as to the arm, and will not be affected by any ordinary jars or shocks incident to the movement of vehicles in which the apparatus may be mounted.

Brackets 35, 35 are adapted for attachment to the structure in which the apparatus is to be installed, by means of screws or the like, not shown, passing through suitable holes 37, 37 therein. These brackets have forwardly projected arms 38, 38, each provided with two upper sockets 39, 39 and two

lower sockets 40, 40, each pair of sockets being connected by a hole 41 passing through the bracket arm.

The frame 1 is also provided with bracket arms 42, 42, each having two sockets 43, 43 on the under side thereof, from which holes 44, 44, extend up through the arms.

A spring 45 is placed in and between each pair of sockets 39, 43; and another spring 10 46 is placed in and below each socket 40; and a securing bolt 47 is passed down through the bracket arms 42, 38 and each of the springs 45, 46, a nut 48 being threaded upon the end of the bolt. These bolts, preferably, have free play through the brackets, so that they may slide therethrough as the springs contract or expand.

Another bracket 50 is provided with suitable holes, 51, 51, or other appropriate means, for facilitating its attachment to the same support which carries the brackets 35, 35; and it has an arm 52, provided with an upper socket 53, and a lower socket 54, connected by a central bore 55.

25 To the lower part of the frame 1 is secured a bracket 56, having a socket 57 in the upper side thereof, from which a hole 58 extends down through the bracket. And in and between the sockets 54, 57 is inserted 30 a spring 59; while in and above the socket 53 is placed another spring 60, a bolt 61 being passed loosely up through the sockets and springs and secured by a nut 62 threaded upon its end.

35 It will be seen, then, that the frame 1 of the apparatus will be carried by the springs 45, 45, 59, interposed between it and the brackets 42, 42, and 57 respectively, so that it is cushioned against any jars or shocks 40 sustained by its supporting structure, the bolts 47, 47 and 61 playing through the brackets to accommodate themselves to the contraction and expansion of the springs, within the limits fixed by the nuts 48, 48

and 62, by means of which the tension of the 45 springs and the amount of play permitted to the frame 1 may be regulated.

By means of my improvements the operation of the placard releasing mechanism is made dependable and positive even under 50 conditions of jar and shock; and the effect of such jars and shocks as railway and trolley cars, or motor busses and like conveyances are subjected to in use is so diminished as not to seriously affect or interfere 55 with the proper functioning of the apparatus.

It will be understood that the means which I have illustrated and described as embodying my improvements is to be considered as 60 typical and not as an exclusive form; for details of construction may be modified, as by the use of equivalents and the like, without departing from the spirit of my invention as described and claimed.

Having thus described my invention, what I claim and desire to secure by Letters Patent of the United States is:—

1. In a display apparatus, the combination of a rotatable placard carrier, a plurality of flexible placards carried thereby, automatic carrier driving means, placard unrolling means embodying a slotted cam race, an arm actuated thereby, and placard engaging elements reciprocated by the arm and a frame in which the apparatus is assembled. 70

2. In a display apparatus, the combination of a rotatable placard carrier, a plurality of flexible placards carried thereby, automatic carrier driving means, placard unrolling means embodying a slotted cam race, 80 formed between a centrally disposed cam and an independently supported surrounding track, an arm actuated thereby, and placard engaging elements reciprocated by the arm and a frame in which the apparatus is assembled. 85

LESLIE R. McDONALD.
